UNITED STATES PATENT OFFICE.

AUGUSTE PACHE, OF NEW YORK, N. Y.

SPARK-PLUG AND PRIMING DEVICE.

1,325,262.

Specification of Letters Patent. Patented Dec. 16, 1919.

Application filed April 20, 1917. Serial No. 163,324.

To all whom it may concern:

Be it known that I, AUGUSTE PACHE, a subject of Switzerland, residing in the city of New York, borough of Manhattan, county 5 and State of New York, have invented a certain new and useful Spark-Plug and Priming Device, of which the following is a specification.

This invention is a spark plug and priming device and is an improvement upon the structure of my prior application Serial No. 95,264, filed May 3, 1916. The object of this prior invention was to provide a device, simple in construction, and the parts of 15 which could be readily dismantled for cleaning purposes, said device being further provided with means whereby the engine with which the plug was associated might be primed through the plug. Said means further allowed of the cleansing of the electrode of the plug without necessitating the removal of the plug from the engine.

In structures of the type exemplified by my prior invention, one of the electrodes is 25 generally made in the form of a pin serving as a valve, which co-operates with a seat formed on a downward projection on the interior of the plug. The provision of the downward projection specified generally 30 causes the formation within the plug of a dead-air space or chamber above the spark gap, and, as this chamber is not provided with an outlet, except at its bottom, which is in communication with the engine cylinder, said chamber, after long continued use 35 of the plug, becomes substantially filled with a deposit of carbon, which it is impossible to remove without taking the plug from the engine and dismantling the same.

40 The object of the present invention is to provide a plug embodying all the features of advantage of my previous plug, but provided with further means whereby carbon deposits may be removed from the said 45 chamber in a simple and efficient manner, and without necessitating the dismantling of the plug or the removal of the same from the engine.

Features of the invention, other than 50 those specified, as well as the advantages thereof, will be apparent from the herein-after detailed description taken in conjunction with the accompanying drawing.

In the accompanying drawing I have illus-

trated one practical embodiment of the invention, but the construction therein shown is to be understood as illustrative, only, and not as defining the limits of the invention.

Figure 1 is a vertical, central section through a combined spark plug and priming device embodying the present invention.

Fig. 2 is a side elevation of said plug, and

Fig. 3 is a transverse section taken in the plane of the line 3—3 of Fig. 1.

Referring to the drawing, A designates 65 a metallic shell threaded, as at a, to screw into a threaded tap of an engine cylinder. The upper portion of shell A is interiorly threaded to receive an exteriorly threaded, tubular plug B, which carries or supports 70 the remaining portions of the spark plug and priming device.

Positioned within plug B is the depending tubular stem c of an insulating block C, through which extends a tubular metallic 75 bushing D. Bushing D is provided intermediate its ends with a shoulder d, adapted to be seated in the base of a recess c' formed in the base of insulating member C. Said insulating block C is provided intermediate 80 its ends with an exterior annular shoulder c'', so that, in assembling the parts, the lower end of insulating block C is inserted into the upper portion of shell A, and thereafter the threaded tubular plug is screwed down 85 upon shoulder c'' to tightly bind insulating block C between plug B and shell A, as clearly shown in Fig. 1. Cushioning washers or gaskets c''' are preferably introduced between the binding surfaces to assure tight 90 joints and preclude leakage.

Bushing D thus constitutes, in effect, the core of the plug and is held in the position shown, to maintain the parts in assembled 95 relation, by means of a nut d', which is screwed onto the upper portion of said bushing, the same being exteriorly threaded to co-operate with said nut. Nut d' seats on a washer d'', superimposed upon the upper face 100 of insulating block C.

Preferably formed integral with nut d', and on the upper portion thereof, is a bowl-shaped vessel E, adapted to contain the hydrocarbon liquid for priming the engine, and said liquid is adapted to flow from the vessel 105 E, through ducts e formed in bushing D at the base of the vessel, into the interior passage of the bushing and down through and

beyond the lower end of said passage into the interior of shell A, thence passing directly into the engine cylinder.

As is generally the case in spark plugs, shell A, which threads into the top of the engine, is metallic and is, accordingly, in electrical connection with the casting of the engine, which is electrically grounded. The shell, therefore, serves as one of the electrodes of the ignition circuit, the other electrode being, in accordance with this invention, embodied in a detachable pin F, slidably positioned within tubular bushing D.

Pin F embodies a metallic member, provided at one end with a threaded stem f, and an adjacent cylindrical portion f', and at its opposite end with a reduced cylindrical portion f''. Adjacent the portion f'' is a portion f³, which is preferably polygonal in cross section and extends from the portion f'' to a short distance from the portion f'. Upon the stem f is adapted to be positioned a thimble g, provided with a laterally extending arm g', carrying at its end an insulating knob G. The thimble seats on the upper end of the cylindrical portion f' and is securely locked in place by a jam-nut screwed on the stem f. The interior of the thimble g is threaded, and the threads thereof are adapted to co-operate with the threaded portion of bushing D, which extends upwardly beyond vessel E, as shown in Fig. 1. Thus, by rotating handle G, the thimble is raised or lowered upon bushing D, with the result that the electrode F is raised or lowered. As stated, the portion f³ of the electrode F is polygonal in cross-section, the purpose of this being to allow the priming fluid introduced into bowl E to circulate downwardly through the passage of the bushing about the polygonal portion, which, because of its shape, does not entirely fill the cylindrical passage of said bushing.

Intermediate the polygonal or squared portion f³ and the reduced portion f'' of electrode F is formed a frusto-conical valve f⁵ adapted to seat, when thimble g is screwed down upon the upper end of bushing D, upon a similarly shaped valve seat d³ formed interior of the bushing, as shown best in Fig. 1. In the normal operation of the engine, thimble g is screwed down so that valve f⁵ is maintained seated to close the passage through the bushing. However, when it is desired to prime the engine, handle G is manipulated to raise the thimble, unseat the valve, and allow the priming fluid to flow downwardly through the interior of said bushing and into the engine cylinder. Upon the conclusion of the priming operation thimble g is again seated by a counter-rotation of handle G, and the engine is free to carry out its normal operations, it being understood that the spark occurs

between the lower end of the electrode F and the fixed electrode a', depending from threaded portion a of the shell. If desired, however, the lower end of shell A may be shaped as shown in my prior application, so that the spark gap is between the lower ends of the shell and electrode. 70

It will, of course, be understood that, in completing the ignition circuit of the engine, the main from the magneto, battery, or coil, is secured to the threaded stem, the other pole of the circuit being grounded, as is common. 75

It is unnecessary, in the carrying out of the priming operation, to detach any of the parts, but merely lift the electrode F a short distance. As a matter of fact, no part is detached during this operation, or left in such position that, if the charge is fired in the engine cylinder, the parts may be blown off, with resulting damage, as has frequently been the case in prior art devices. 80 It will, however, be manifest that, when thimble g is raised as specified, communication will be opened between the combustion chamber of the engine and the outer atmosphere through the bushing of the plug. Moreover, even though electrode F is raised sufficiently to open such communication, the lower end of said electrode 85 remains in operative relation to the other electrode a', so that the ignition circuit is not rendered inoperative by the elevation of electrode F, and the engine may continue to operate even though said electrode is elevated as described. This is an important advantage, hereinafter manifest, and enables the plug to accomplish an important function, since it will be manifest that, if an outlet for the pressure in the engine is 90 provided through the plug, the out-rush of gases through the plug, when the charge in the engine cylinder is fired, will accomplish a scouring action upon the electrodes, as well as on the entire passage leading to 95 the outer atmosphere. This scouring action will serve to remove all carbon deposits from the electrodes, the chamber in the lower end of the plug, and the passages and ducts of said bushing. 100

My prior construction was capable of this general result, but was open to the objection that the dead-air chamber hereinbefore specified was not freed of carbon deposits during the blowing-off or scavenging operation. The same chamber is incorporated in the plug of this invention and is embodied in the recess c at the base of the insulating block and the communicating interior passage through the threaded portion of shell 110 A. However, in accordance with this invention, said chamber is not a dead-air chamber, but is, in effect, a circulation chamber, since a plurality of passages or holes 115 I are provided through the bushing below 120 125 130

the valve seat d to open communication between said chamber and the interior passage through the bushing. With this construction, the lifting of the valve will allow 5 of the passage of the engine pressure not only directly up through the passage through the bushing and around electrode F, but, also, through said chamber and passages I into the interior of said bushing. 10 The force of these scavenging gases is very great, so that the carbon deposits within the heretofore dead-air chamber are carried off, and clogging or short-circuiting of the plug is precluded. 15 If the operation of scavenging the plug, as described, is carried on from time to time, and at such intervals as not to allow of too heavy a deposit of carbon, the most beneficial results are accomplished, since, mani- 20 festly, a relatively small deposit of carbon may be more readily removed than a comparatively heavy coating or body of such material. For all normal conditions, the freeing of the plug of carbon may be ac- 25 complished in the manner specified without necessitating the dismantling of any part of the plug. However, if desired, electrode F may be readily removed or withdrawn from bushing D by unscrewing the thimble be- 30 yond its priming position sufficiently to release the same from the threads of the bushing. When thus removed, electrode F may be scraped, sand-papered, or otherwise operated upon, from time to time, and again 35 properly positioned in the plug by revers- ing the detaching operation.

It will be noted from Fig. 1 that the bushing D extends downwardly substantially to the lower end of the plug, and it 40 thus forms a guide for electrode F. Accordingly, even though the reduced lower end f^2 of said electrode becomes highly heated, the electrode will not get out of plumb and short-circuit through the lower end of 45 shell A. This is an important advantage, since it is well known that the temper is drawn from the electrodes of the plug and a jar of the engine is likely to bend a long, thin electrode sufficiently to short-circuit the 50 plug at the point where the spark normally occurs. This cannot result in the plug of this invention, as the lower end of the bushing serves to steady the lower end of elec- 55 trode F, while in its heated condition.

55 It will be manifest from the foregoing de- scription that the present invention em- bodies many features of novelty which, when employed in combination, produce a prim- ing plug of greatly increased efficiency. It 60 will be understood, however, that many ad- vantages of the invention may be obtained through the employment of some of the fea- tures individually, without necessarily em- ploying all. The invention is, therefore, to 65 be understood as not limited to the specific

showing made, but as broadly novel as is commensurate with the appended claims.

Having thus fully described the invention, what I claim as new, and desire to secure by Letters Patent, is:

70 1. A device of the class described embodying a spark plug provided with a core mem- ber having a longitudinal passage there- 75 through, an attaching shell for mounting the plug in operative relation to an internal combustion engine, the shell being spaced from the core member at the lower portion of the plug to provide a chamber, ducts lead- ing from said chamber to the passage through the core, and means for normally sealing said passage, said means being oper- 80 able to unseal the passage to allow the pres- sure within the engine cylinder to be ex- hausted through the chamber, ducts, and the 85 passage of the core, for the purpose of scav- enging the parts of carbon deposits.

2. A device of the class described embodying a spark plug provided with a core mem- ber having a longitudinal passage there- 90 through, an attaching shell for mounting 95 the plug in operative relation to an internal combustion engine, the shell being spaced from the core member at the lower portion of the plug to provide a chamber, ducts leading from said chamber to the passage 100 through the core, and a valve for normally sealing said passage, said valve being oper- able to unseal the passage to allow the pres- 105 sure within the engine cylinder to be ex- hausted through the chamber, ducts, and the 110 passage of the core, for the purpose of scav- enging the parts of carbon deposits.

3. A device of the class described embodying a spark plug provided with a core mem- ber having a longitudinal passage there- 115 through, an attaching shell for mounting the plug in operative relation to an internal combustion engine, the shell being spaced from the core member at the lower portion of the plug to provide a chamber, ducts lead- 120 ing from said chamber to the passage through the core, a rod extending longitudinally of said passage, a valve associated with said rod, and means for raising and lower- 125 ing the rod to unseat or seat the valve, whereby, when the valve is unseated, the pressure in the engine cylinder is exhausted through said passage and ducts for the purpose of scavenging the parts of carbon de- 130 posits.

4. A device of the class described em- bodying a spark plug provided with a core mem- ber having a longitudinal passage there- 135 through, an attaching shell for mounting the plug in operative relation to an internal combustion engine, the shell being spaced from the core member at the lower portion of the plug to provide a chamber, ducts leading from said chamber to the passage through the core, means for normally seal-

- ing said passage, said means being operable to unseal the passage to allow the pressure within the engine cylinder to be exhausted through the chamber, ducts, and the passage 5 of the core, for the purpose of scavenging the parts of carbon deposits, said passage also serving to convey priming fluid into the engine cylinder when the engine is at rest, and means for feeding said priming fluid 10 to said passage.
5. A device of the class described embodying a spark plug provided with a core member having a longitudinal passage there-through, an attaching shell for mounting 15 the plug in operative relation to an internal combustion engine, the shell being spaced from the core member at the lower portion of the plug to provide a chamber, ducts leading from said chamber to the passage 20 through the core, means for normally sealing said passage, said means being operable to unseal the passage to allow the pressure within the engine cylinder to be exhausted through the chamber, ducts, and the passage 25 of the core, for the purpose of scavenging the parts of carbon deposits, said passage also serving to convey priming fluid into the engine cylinder when the engine is at rest, and a priming vessel for feeding said 30 priming fluid to said passage.
6. A device of the class described embodying a spark plug provided with a core member having a longitudinal passage there-through, an attaching shell for mounting 35 the plug in operative relation to an internal combustion engine, the shell being spaced from the core member at the lower portion of the plug to provide a chamber, ducts leading from said chamber to the passage 40 through the core, a rod extending longitudinally of said passage, a valve associated with said rod, and means for raising and lowering the rod to unseat or seat the valve, whereby, when the valve is unseated, the 45 pressure in the engine cylinder is exhausted through said passage and ducts for the purpose of scavenging the parts of carbon deposits, said rod serving as one of the electrodes of the plug.
- 50 7. A device of the class described embodying a spark plug provided with a core member having a longitudinal passage there-through, an attaching shell for mounting the plug in operative relation to an internal 55 combustion engine, the shell being spaced from the core member at the lower portion of the plug to provide a chamber, ducts leading from said chamber to the passage through the core, a rod extending longitudinally of said passage, a valve associated 60 with said rod, means for raising and lowering the rod to unseat or seat the valve, whereby, when the valve is unseated, the pressure in the engine cylinder is exhausted 65 through said passage and ducts for the purpose of scavenging the parts of carbon deposits, said rod serving as one of the electrodes of the plug.
- pose of scavenging the parts of carbon deposits, said rod serving as one of the electrodes of the plug and the attaching shell constituting the other electrode, and means for securing one lead of the ignition circuit 70 to said rod.
8. In a device of the class described, a spark plug provided with a longitudinal passage, a vessel, ducts communicating with the vessel and said passage, a rod slidable 75 longitudinally of said passage and provided with means for sealing the passage, said rod serving as one of the electrodes of the plug, a chamber in the lower end of said plug, ducts leading from the chamber to the 80 longitudinal passage of the plug, and means for moving the rod into a position to open said passage to allow the pressure within the engine, with which the plug is associated, to be exhausted through the chamber, 85 ducts, and the longitudinal passage of the plug, for the purpose of freeing the parts of carbon deposits, said ducts and passage serving to convey a priming fluid deposited within the vessel to the interior of the engine cylinder, when the engine is at rest.
9. A device of the class described embodying a spark plug having an insulating member, a tubular core member extending through the insulating member and beyond 95 the lower edge thereof, an attaching shell mounted on the insulating member and also extending below the lower edge of the same to form a chamber intermediate the shell and the core member at the lower portion of the 100 plug, ducts leading from said chamber into the interior of the tubular core and valve mechanism for sealing or unsealing the passage through said core, said passage serving, when unsealed, to allow of the exhaust 105 of the pressure within the engine cylinder through the plug for the purpose of freeing the parts of carbon deposits.
10. A device of the class described embodying a spark plug having an insulating 110 member, a tubular core member extending through the insulating member and beyond the lower edge thereof, an attaching shell mounted on the insulating member and also extending below the lower edge of the same 115 to form a chamber intermediate the shell and the core member at the lower portion of the plug, ducts leading from said chamber into the interior of the tubular core, and valve mechanism for sealing or unsealing the passage through said core, said passage serving, when unsealed, to allow of the exhaust 120 of the pressure within the engine cylinder through the plug for the purpose of freeing the parts of carbon deposits when the engine is operating, and allowing the introduction of priming fluid into the engine cylinder when the engine is at rest.
11. A device of the class described embodying a spark plug having an insulating 125

- member, a tubular core member extending through the insulating member and beyond the lower edge thereof, an attaching shell mounted on the insulating member and also 5 extending below the lower edge of the same to form a chamber intermediate the shell and the core member at the lower portion of the plug, ducts leading from said chamber into the interior of the tubular core, an 10 electrode extending longitudinally through the passage of the core, valvular means associated with said electrode, and means for shifting the electrode longitudinally of said passage to seal or unseal the passage, said 15 passage serving, when unsealed, to allow of the exhaust of the pressure within the engine cylinder through the plug for the purpose of freeing the parts of carbon deposits when the engine is operating, and allow of 20 the introduction of priming fluid into the engine cylinder when the engine is at rest.
12. A device of the class described embodying a spark plug provided with a core member having a longitudinal passage 25 therethrough, an attaching shell for mounting the plug in operative relation to an internal combustion engine, the shell being spaced from the core member at the lower portion of the plug to provide a chamber, 30 ducts leading from said chamber to the passage through the core, an electrode consisting of a rod extending longitudinally of
- said passage with a part shaped to conform with a corresponding part of the core to form a valve and means for raising and 35 lowering the rod to unseat or seat the valve, whereby, when the valve is unseated, the pressure in the engine cylinder may be exhausted through said passage and ducts for the purpose of scavenging the parts of carbon deposits, or the engine may be primed 40 through said core.
13. A spark plug embodying an insulating member, a tubular core member extending through the insulating member and beyond 45 the lower edge thereof, an attaching shell mounted on the insulating member and also extending below the lower edge of the same to form a chamber intermediate the shell of the core member at the lower portion of 50 the plug, ducts leading from said core chamber into the interior of the tubular core, a pin, forming an electrode, extending through the tubular core, said pin having formed thereon a valve for sealing or unsealing the passage through the core, means for raising said pin so as to permit the engine pressure to escape through, and clean, 55 the plug, without interfering with the ignition circuit of the plug. 60

In testimony whereof I have signed my name to this specification.

AUGUSTE PACHE.
